UNITED STATES PATENT OFFICE

2,433,300

SUBDRAIN

George E. Shafer, Middletown, Ohio, assignor to
The American Rolling Mill Company, Middle-
town, Ohio, a corporation of Ohio

Application February 23, 1946, Serial No. 649,506

10 Claims. (Cl. 61—11)

1

This invention relates to a subdrain and more particularly to a subdrain made from sheet metal. In the past sheet metal subdrains have not been used to the maximum extent because they could not be manufactured at a low enough cost to compete with clay tile.

It is, therefore, an object of the present invention to provide a simple sheet metal subdrain which is susceptible of manufacture at a price which will put it in competition with clay tile. It is another object of my invention to provide a subdrain in which the principal strength against collapse is in one half the periphery, preferably the upper half.

It is another object of my invention to so design the other half that it will hold its principal shape and yet deflect and cooperate with the opposite half. It is another object of my invention to provide for stiffening of the lower half without offering substantial resistance to the flow of water through the drain and yet to provide for sufficient eddy currents to keep the drain clean.

Another object of my invention is to provide a subdrain which does not need to be perforated and yet which will allow water to enter in such a way that solids would have to move against gravity to enter the drain.

Further objects of my invention include the provision of a subdrain in which the sections will be completely nestable so that shipping space is economized, and which can be quickly and easily assembled with only a pair of common pliers.

These and other objects of my invention which will be described in more detail hereinafter or which will be apparent to one skilled in the art upon reading these specifications I accomplish by that construction and arrangement of parts of which I shall now describe exemplary embodiments.

Reference is made to the drawings forming a part hereof and in which Figure 1 is an end elevation view of one embodiment of my invention.

Figure 2 is a plan view of the same as seen from above.

Figure 3 is a side elevational view of the same.

Figure 4 is a partial bottom view of the same.

Figure 5 is a partial detailed cross-sectional view on an enlarged scale taken on the line 5—5 of Figure 2.

Figure 6 is a partial elevational view of a modification of my invention, and Figure 7 is a partial cross-sectional view of the same on the line 7—7 of Figure 6.

Briefly in the practice of my invention I make my subdrain in two halves; an upper half in-

2

dicated generally at 10 and a lower half indicated generally at 11. The upper half will preferably be corrugated transversely in order to give it arch strength against crushing while the lower half will preferably be designed for favorable flow characteristics. The joint between the upper and lower halves is such as to provide for bracing of the weaker (lower) half by the stronger (upper) half, and to provide a desirable type of waterway opening into the subdrain without requiring perforation of the pipe.

In the embodiment of Figs. 1—5 inclusive, the upper half will have the longitudinal edges bent upwardly and then again downwardly in a reverse curve as indicated at 12. The lower half will not be corrugated in the conventional sense of the word, but will have angular ribs 14 formed therein for the purpose of strengthening the lower half of the drain and also for the purpose of providing for a certain amount of eddy currents in order to keep the conduit clean. As will be clear from a consideration of Figures 1 and 4 the members 14 are preferably tapered as to width and depth so that there will be a minimum of interference with flow since the bottom of the drain will be substantially smooth as indicated at 13. The longitudinal edges of the lower half of section 11 will be bent outwardly in a reverse curve as indicated at 15. The curvature 15 and the curvature 12 will be the same so that the upper section 10 of the drain rests upon the lower section of the drain with the members 12 of the upper section fitting over the members 15 of the lower section.

If it is felt desirable to secure the two halves together, it is only necessary to bend lips 12a inwardly to engage under the members 15 as shown in Figure 5. This can easily be done with a pair of pliers.

By reference to Figures 4 and 5, it will be observed that a series of openings 16 are formed between the upper side of the member 15 and the lower side of the member 12 by virtue of the fact that the member 15 is smooth and the member 12 is corrugated. By particular reference to Figure 5 it will be clear that the openings 16 form inverted U-shaped passages communicating with the interior of the drain, so that water can enter the drain as indicated by the arrow 17 in Figure 5. The broken line 18 illustrates the water table and it will be clear that solid matter would have to go against the force of gravity to enter into the drain while water will enter as long as the water table is as indicated at 18 or higher.

In order to stagger the circumferential seams it may be desirable to provide, for any given

length of subdrain, one upper member and one lower member which are shorter than the standard length. The short upper member may be used at one end and the short lower member at the other end, whereby no circumferential seam will be continuous around the pipe.

From the foregoing description it will be clear that this subdrain is very simple to install because it is only necessary to lay the upper half on top of the lower half and, if desired, crimp in a series of lips 12a and to lay the assembled drain in a ditch which can then be filled in. It will also be clear that by virtue of the construction of the lower half of the drain, there is very little interference with the flow of water while at the same time this section has strengthening means giving it a good beam strength. It will also be clear that the upper section by virtue of its form, has great crushing strength and that by virtue of the connection between the two sections an entry way is provided for water while solid matter is not permitted to enter.

In Figs. 6 and 7 I have illustrated a still more inexpensive embodiment of my invention, embodying the same fundamental principles set forth above. The upper half is designated 10a and the lower half 11a, and as will be clear from the figures, these sections are structurally like those of Figures 1 to 5 inclusive. However, I employ a modified joint structure which is considerably cheaper. I strike out a series of lips 15a, preferably along the edges of the lower half section, and assemble the conduit by simply fitting the edges of the upper half section between the edges of the lower half section and the lips 15a. In this way there are provided at 16a a series of waterway openings into the subdrain structure, so that a separate perforating operation is unnecessary.

It will be clear that numerous modifications may be made without departing from the spirit of my invention and I, therefore, do not intend to limit myself except as pointed out in the claims as follows. Having now fully described my invention, what I claim as new and desire to secure by Letters Patent is:

1. A sheet metal drain structure comprising upper and lower arcuate half sections, said upper half sections being formed primarily for strength characteristics, said lower half sections being formed primarily for flow characteristics, but having strengthening configurations starting near the center line thereof and becoming increasingly pronounced toward the longitudinal edges thereof, and longitudinal joints between said upper and lower half sections, said joints providing waterway openings into said drain structure.

2. A sheet metal drain structure comprising upper and lower arcuate half sections, said upper half sections being transversely corrugated in order to give said half sections arch strength characteristics, said lower half sections having strengthening grooves extending from substantially the edges thereof to near the center line leaving a substantially smooth bottom for better flow characteristics, and longitudinal joints between said sections providing waterway openings into said drain structure.

3. A sheet metal drain structure comprising upper and lower arcuate half sections, both of said sections having their longitudinal edges bent upwardly, outwardly and downwardly to form inverted U-shaped members mating together, one of said inverted U-shaped members being corrugated and the other being free of corrugations,

whereby there are formed between said U-shaped members a series of inverted U-shaped passageways.

4. A sheet metal drain structure comprising upper and lower arcuate half sections, said upper section having peripheral corrugations and having its longitudinal edges bent back upon themselves and then outwardly and downwardly to form inverted U-shaped members, said lower section having its longitudinal edges bent over outwardly and downwardly to form inverted U-shaped members mating with said first-mentioned U-shaped members, said second-mentioned U-shaped members being free of corrugations whereby there are formed between said U-shaped members a series of inverted U-shaped passageways.

5. A sheet metal drain structure comprising upper and lower arcuate half sections, said upper section having peripheral corrugations and having its longitudinal edges bent back upon themselves and then outwardly and downwardly to form inverted U-shaped members, said lower section having its longitudinal edges bent over outwardly and downwardly to form inverted U-shaped members mating with said first-mentioned U-shaped members, said second-mentioned U-shaped members being free of corrugations whereby there are formed between said U-shaped members a series of inverted U-shaped passageways, and lips bent inwardly from the edges of said first-mentioned U-shaped members and engaging under the edges of said second-mentioned U-shaped members.

6. A sheet metal drain structure comprising upper and lower arcuate half sections, said upper section having peripheral corrugations and having its longitudinal edges bent back upon themselves and then outwardly and downwardly to form inverted U-shaped members, said lower section having tapered angularly disposed grooves extending from near the edges to near the center line of said section leaving a central portion thereof substantially smooth, said lower section having its longitudinal edges bent over outwardly and downwardly to form inverted U-shaped members mating with said first-mentioned U-shaped members, and lips bent inwardly from the edges of said first-mentioned U-shaped members and engaging under the edges of said second-mentioned U-shaped members.

7. A sheet metal drain structure comprising upper and lower arcuate half sections, said upper section having peripheral corrugations and having its longitudinal edges bent back upon themselves and then outwardly and downwardly to form inverted U-shaped members, said lower section having angularly disposed grooves extending from near the edges to near the center line of said section leaving a central portion thereof substantially smooth, said lower section having its longitudinal edges bent over outwardly and downwardly to form inverted U-shaped members mating with said first-mentioned U-shaped members, and lips bent inwardly from the edges of said first-mentioned U-shaped members and engaging under the edges of said second-mentioned U-shaped members.

8. A sheet metal drain structure comprising upper and lower arcuate half sections, said upper section having peripheral corrugations and having its longitudinal edges bent back upon themselves and then outwardly and downwardly to form inverted U-shaped members, said lower section having angularly disposed grooves ex-

tending from near the edges to near the center line of said section, said grooves being narrower and shallower adjacent said center line whereby the center portion of said section is substantially smooth, said lower section having its longitudinal edges bent over outwardly and downwardly to form inverted U-shaped members mating with said first-mentioned U-shaped members, and lips bent inwardly from the edges of said first-mentioned U-shaped members and engaging under the edges of said second-mentioned U-shaped members.

9. A sheet metal drain structure comprising upper and lower arcuate half sections, said upper half sections being transversely corrugated in order to give said half sections arch strength characteristics, said lower half sections having strengthening grooves extending from substantially the edges thereof to near the center line leaving a substantially smooth bottom for better flow characteristics, a series of lips struck out from the edges of one of said half sections, the edges of the other of said half sections seated between the edges of said one of said half sections and said lips, said joints forming waterway 25 openings into said drain structure.

10. A sheet metal drain structure comprising upper and lower arcuate half sections, said upper half sections being transversely corrugated in order to give said half sections arch strength characteristics, said lower half sections having strengthening grooves extending from substantially the edges thereof to near the center line leaving a substantially smooth bottom for better flow characteristics, a series of lips struck out from the edges of said lower half sections, the edges of said upper half sections seated between the edges of said lower half sections and said lips, said joints forming waterway openings into said drain structure.
